H. C. MARTIN.
RECORDING AND REPRODUCING INSTRUMENT.
FILED JAN. 23, 1922.

Inventor
HENRY C. MARTIN

C. C. Clements.

Attorney

UNITED STATES PATENT OFFICE.

HENRY C. MARTIN, OF ELKHART, INDIANA.

RECORDING AND REPRODUCING INSTRUMENT.

Application filed January 23, 1922. Serial No. 531,233.

To all whom it may concern:

Be it known that I, HENRY C. MARTIN, a citizen of the United States of America, residing at Elkhart, in the county of Elkhart and State of Indiana, have invented certain new and useful Improvements in Recording and Reproducing Instruments, of which the following is a specification.

The subject matter of the present invention relates particularly to the construction of the sound box and tone arm of the recording or reproducing instrument whereby the sound box may be joined to the tone arm in such manner as to permit facile adjustment 10 of the sound box, its conveyer arms and the needle or stylus, to various and numerous angular positions with relation to the plane of the recording or reproducing record or disk. By the utilization of my invention the 15 sound waves or vibrations arising from the conveyer arms through the diaphragm, or passing to the conveyer arms through the diaphragm, are in the first instance collected in the sound box above the diaphragm and 20 passed therethrough without interference or obstruction to the tone arm. When the instrument is recording sounds, the sound waves or vibrations are carried to the sound box above the diaphragm where sufficient 25 space is provided to insure proper and uninterrupted distribution of the sound waves to the diaphragm and to the multiplicity of sound conveyer-arms attached to the dia- 30 phragm. The parts of the sound box and 35 its head are so combined and arranged that the sound box may readily be detached from the tone arm, and may with equal facility be loosened with relation to the tone arm for adjustment to desired angular position, and 40 may also be rigidly affixed thereto in desired adjusted position. The tone arm utilized in connection with the sound box also involves 45 novel features of construction whereby the partials or fractions of sounds are assisted in their development and amplification, in addition to that afforded by their passage through the dome shaped sound box, before the sound waves arrive at the amplifier proper, thus rendering the production of 50 tones and sound in a more facile manner.

In the accompanying drawings I have illustrated one complete example of the physical embodiment of my invention wherein the parts are combined and arranged according 55 to the best mode I have thus far devised for

the practical application of the principles of my invention.

Figure 1 is a view in side elevation of the sound box in vertical position, or perpendicular to the record disk, showing also the tone arm in section, together with the elbows and joints for supporting the tone arm and sound box.

Figure 2 is a top plan view of the sound box, detached from the tone arm.

Figure 3 is a vertical sectional view through the sound box, showing some of the conveyer arms in elevation.

It will be understood that the sound box is adapted for use with a revolving cylinder 70 or rotary disk record as usual, and that the stylus or needle travels in the groove for the reproduction of sound, and also performs its usual functions in the operation of recording.

The sound box is supported above the disk record by the tone arm designated as a whole by the numeral 1, which has a series of elbows at 2, properly articulated and supported on the vertical tubular member 3, 80 which is connected with the amplifier, not shown. The tone arm is adapted to swing in a vertical plane with its center of movement at the elbows 2, and also is designed to swing in a horizontal plane with its 85 center of movement at 3' in the vertical tubular member 3. Linear adjustment of the sound box, toward or away from the pivotal centers 2 and 3' may be accomplished by extending or contracting the tone 90 arm which includes an inner tubular section 4 that may be moved relatively to its outer casing 1. This adjustment of the length of the tone arm brings the voice, or sound from the sound producing device, to be recorded 95 closer to the diaphragm of the sound box and the record, to increase the force of the vibrations at the recording point, or vice versa.

At its outer end the inner section 4 of the tone arm is provided with a fixed frictional clamp-sleeve 5 having perforated ears 6 at the sides of a slot and a clamp screw 7 therein for clamping the sleeve on the upper end of a curved elbow 8 which connects the tone 105 arm and sound box.

The elbow may thus be adjusted at an angle to the longitudinal axis of the tone arm and fixed by means of the screw 7 in desired position. At the lower or outer end 110

of the elbow 8 a second clamp sleeve, as 9 is secured, by means of which the sound box is connected with the elbow, and this clamp sleeve is also slotted and fashioned with 5 perforated ears 10 and a set screw 11.

The top of the sound box 12 is of metal, open at its center and dome shaped, or spherical with its convex face on the outer side or top and the concave inner portion 10 forms a space for collecting or distributing sound waves or vibrations for recording and reproducing respectively.

In connection with the spherical top 12 of the sound box I employ a tubular head 13, secured at its upper end, in alinement with the elbow 8, within the resilient end of the clamp sleeve 9, and at its lower end this tubular head is fashioned with a flaring, concavo-convex or spherical flange 14, its 20 curved lines being struck from the same center as are those of the top or dome shaped portion 12. Between the flange 14 and the inner face of the spherical head 12 is interposed a washer or gasket 15, of felt, leather, 25 or other non-conducting material adapted to be frictionally engaged between these two elements. On its exterior the tubular head 13 is provided with screw threads 16 intermediate its height, that are adapted to receive the nut 17 which is knurled on its exterior for facility in turning. A metallic washer 18 is located below the nut, and between this washer and spherical head 12 a non-conducting gasket 19 is interposed. The 30 spherical head 12, gaskets 14 and 19, and metallic washer 18 have open centers, the spherical head especially being so fashioned in order that the latter may be adjusted at any angle (within limits) to the perpendicular, for tilting the sound box. Thus by slightly turning backward the nut 17 in Figures 1 and 2, the spherical head 12 may be released and the sound box moved to adjusted position, then by tightening the 40 nut the spherical head is clamped and frictionally held between the two gaskets and the flange 14 and washer 18.

Below the flanged spherical head, a flanged retaining ring 20 is secured, by 50 means of screws 21 passing through these elements at their peripheries, and the diaphragm, 22, preferably of mica, and concavo-convex in form, is secured at its circular edges between the flanged ring and a non-conducting gasket or ring 23.

There are illustrated five sound transmitting or conveyer arms 24, having their outer ends brought together at 25, above the needle or stylus 26, and the upper ends of these 60 arms are connected at 27 with the diaphragm. A stylus holder 28 is formed intermediate of the bracket arms 29, which form a U-shape structure attached beneath the retaining ring 20, and non-conducting material 65 as 30 is interposed between the stylus holder

28 and the ends 25 of the arms, the usual set screw 31 being employed for holding the needle.

The arms are joined integrals, as at 25, and are of varying lengths, bent to bowed 70 shape as shown in order to insure a comparatively long path of travel of sound waves between the stylus and the diaphragm, or between the diaphragm and the stylus, and because of this varied 75 length, the travel of the sounds carried is also varied. The size and carrying capacity of the arms also varies, for it will be noted that the cross sectional area of the arms increases from the point of attachment to 80 the diaphragm to the junction of the several arms in the stylus holder. By this variation in size and length the arms are adapted to receive and convey various tones or vibrations. 85

Having thus fully described my invention, what I claim as new and desire to secure by Letters Patent is—

1. The combination with a tone arm and a tubular head, of a sound box including an 90 open-center spherical head surrounding said tubular head, a complementary flange on the tubular head, and means on the tubular head for clamping together the spherical head with relation to the flange. 95

2. The combination in a sound box with its diaphragm and an open-center spherical head forming a space above the diaphragm, of a tubular supporting head having a complementary flange within said spherical 100 head, and means for clamping said spherical head in adjusted position on said flange.

3. The combination with a supporting, tubular head having exterior threads and an annular spherical flange, of a sound box 105 having an open-center spherical head, and a nut on the threaded head, whereby said nut is adapted to hold the spherical head in adjusted position on the spherical flange.

4. The combination with a tone arm and 110 an elbow, of a detachable sound box including a tubular supporting head, a clamp sleeve on said elbow engaging said head and an adjusting head on said sound box; and means for securing said adjusting head 115 in fixed position with relation to the tubular head.

5. The combination with a tone arm, a detachable elbow having a clamping sleeve, and a tubular head fitted in said sleeve, exterior threads on said head and a spherical flange at the end of said head, an open-center spherical head forming a portion of a sound box, and a clamp nut on said tubular head, whereby said spherical head may be 120 retained in adjusted position with relation to said flange. 125

In testimony whereof I affix my signature.

HENRY C. MARTIN.
